(57) **CLAIM**

The ornamental design for a buckle closure, substantially as shown and described.

DESCRIPTION

FIG. 1 is a perspective view of a buckle closure with a standoff according to the present invention;

FIG. 2 is a plan view of a top side of the buckle closure shown in FIG. 1;

FIG. 3 is an elevation view of a front side of the buckle closure shown in FIG. 1;

FIG. 4 is an elevation view of a left side of the buckle closure shown in FIG. 1;

FIG. 5 is an elevation view of a right side of the buckle closure shown in FIG. 1; and,

FIG. 6 is an elevation view of a bottom side of the buckle closure shown in FIG. 1.
